US00D631204S

(12) **United States Design Patent**
Dubitsky et al.

(10) **Patent No.:** **US D631,204 S**
(45) **Date of Patent:** ** *Jan. 18, 2011

(54) **LIP BALM CASE**

(75) Inventors: **Craig Dubitsky**, Westfield, NJ (US);
Dennis Payongayong, Brooklyn, NY (US); **Coral Garvey**, Brooklyn, NY (US)

(73) Assignee: **The Kind Group**, New York, NY (US)

(**) Term: **14 Years**

(21) Appl. No.: **29/314,082**

(22) Filed: **Mar. 3, 2009**

(51) LOC (9) Cl. **28-03**

(52) U.S. Cl. **D28/82**; D28/88; D9/519; D9/551

(58) **Field of Classification Search** D28/76-77, D28/82, 85-90; D9/503-504, 519, 551, D9/443; 132/316-318, 320; 206/385, 581, 206/823

See application file for complete search history.
